FIG. 6.

UNITED STATES PATENT OFFICE.

FRANK C. TABLER, OF ST. LOUIS, MISSOURI.

AIR INLET DEVICE FOR INTERNAL-COMBUSTION ENGINES.

1,402,110.

Specification of Letters Patent. Patented Jan. 3, 1922.

Application filed November 17, 1919, Serial No. 338,657. Renewed May 23, 1921. Serial No. 471,969.

To all whom it may concern:

Be it known that I, FRANK C. TABLER, a citizen of the United States, residing at the city of St. Louis, State of Missouri, have 5 invented a certain new and useful Improvement in Air Inlet Devices for Internal-Combustion Engines, of which the following is a full, clear, and exact description, such as will enable others skilled in the art 10 to which it appertains to make and use the same, reference being had to the accompanying drawings, forming part of this specification.

My invention has relation to improvements in air inlet and mixing devices to be applied to the intake manifold of an internal combustion engine, and it consists in the novel details of construction more fully set forth in the specification and pointed out in 20 the claims.

The present invention is an improvement over my pending application for an air inlet device, filed October 25, 1919, Serial No. 233,140, and its object is to provide an inlet device that may be controlled by a spark control rod now present in all automobiles with 25 internal combustion engines.

Further objects are to provide such a device having a suitable coil or pipe through 30 which the air passes before entering the manifold; to provide such device with a valve that may be used on practically any make of automobile; and to provide an air inlet valve that is simple and can be cheaply 35 constructed.

Other and further advantages will be better apparent from the detailed description of the invention in connection with the accompanying drawings, in which:

40 Figure 1 is a side elevation of an internal combustion engine with my invention applied thereto.

Figure 2 is a longitudinal section through the valve on the line 2—2 of Figure 3.

45 Figure 3 is a side elevation of the valve.

Figure 4 is a cross-sectional detail through the valve, showing said valve in closed position, on the line 4—4 of Figure 2.

50 Figure 5 is a section similar to Figure 4, showing the valve in open position.

Figure 6 is a sectional detail showing the baffle cone in the intake manifold.

55 Figure 7 is a diagrammatic view showing the relative movement of the valve ports from closed to open position.

Referring to the drawings, E represents an internal combustion engine provided with an intake manifold M, a spark control rod R and a carburetor C communicating with the manifold. A valve V is mounted on the 60 spark control rod, and a suitable baffle cone 1 is mounted in the manifold, a pipe 2 connecting said cone and valve by a union 3. This pipe passes through a space S between the engine cylinders. 65

The valve V is composed of sections 4, 4, said sections being adapted to envelope the spark control rod R on which they are mounted, and each section of the valve is provided with an annular flange 5 and valve proper 70 6, there being an annular recess r between said flange and valve proper. Said sections are further provided with hub portions 7, each hub portion having oppositely disposed lugs 8, 8, a bolt b being adapted to pass 75 through the lugs of each section, thereby securely clamping said sections together on the spark control rod. A valve casing 9, also in sections, is adapted to enter the annular recesses r, r of the valve proper, being 80 loosely fitted therein. The valve casing is provided with a boss 10, there being an outlet opening 11 in said boss, and opposite the outlet opening 11 is a suitable slotted intake opening 12. The valve 6 is provided 85 with a pair of intake ports 13, 13 triangular in shape, said ports being disposed to register with the intake opening 12 of the casing, upon rotation of the valve in either direction. Each port 13 has a corresponding 90 elongated outlet port 14, the outlet ports being so disposed as to register with the outlet opening 11 in the casing when the valve is rotated to open position.

The operation of my invention may be 95 described as follows: Normally valve V is closed, the ports being disposed as shown in Figure 4. It will be observed that the ports 13, upon the rotation of the valve in either direction, will have to travel a short distance before registering with the intake opening 12. This is to enable the operator to start his car before any air will be admitted to the valve V, it being well understood in the art that upon starting an internal 100 combustion engine the spark lever (not shown) is advanced a short distance. Upon starting the car, it is desirable to have a rich mixture in the cylinders, consequently, the valve V should not be open at this time. 110

However, when the engine is running smoothly, it is desirable to admit air into the manifold in order to rarefy the mixture somewhat, and this is done by opening 5 the valve V. The valve V is mounted upon the spark rod R and with the rotation of said spark rod in a given direction, the valve V will likewise rotate, thus bringing either of the ports 13 into register with the opening 12. Atmospheric air can now enter the valve through said ports, passing out of the valve through the ports 13 and 11, also in register, then through the pipe 2, finally discharging into the manifold through the 10 cone 1.

The cone 1 is here shown as made of wire gauze, thus permitting the air as it reaches the cone to discharge freely into the manifold. The cone also serves to intercept the 15 mixture coming from the carburetor, some of said mixture passing into the cone and some of the mixture tending to draw the air in the pipe 2 into the manifold. The pipe 2 is here shown coiled back and forth between the cylinders, thus insuring that the air passing through the coil will become thoroughly heated before it enters the manifold. This is very desirable for the reason 20 that the mixture in the manifold is highly vaporized, and if the air entering the manifold from the pipe 2 were not heated there would be a tendency to condense said mixture.

In the drawings, the spark rod R is shown 25 on one side of the engine, the intake manifold being on the opposite side, making it necessary to pass either through or around the engine with the coil in order to reach said manifold. However, by using a coil 30 to connect the valve and manifold, it is apparent that regardless of the position of said rod and manifold, a suitable connection can be made.

It will be observed that the intake ports 45 13 of the valve are triangular in shape, which renders it possible to secure any amount of opening desired for, as the port 13 registers with the opening 12, the communication with the outside air can be 50 increased from a mere point to the entire size of the port 13. This is readily apparent by reference to Fig. 7, the closed position of the ports being shown full, the opening or registering position being shown dotted.

55 From the foregoing description, it is readily apparent that any amount of atmospheric air desired may be admitted to the intake manifold when the engine is running. It is also apparent that when the 60 engine is running very slow, or upon starting same, the spark rod R may be rotated the desired distance without affecting the valve V,—a very desirable feature, since

valve V should not be opened upon starting the engine.

Obviously, the present invention is susceptible of modification and improvements without departing from the spirit thereof, and I do not wish to be restricted to the particular construction herein shown.

What I claim is:

1. In combination with an internal combustion engine provided with an intake manifold, a spark control rod, and a valve on said rod and communicating with the 75 manifold.

2. In combination with an internal combustion engine provided with an intake manifold and a spark control rod, a rotatable valve mounted on said rod and communicating with the manifold, and a stationary valve casing surrounding said valve. 80

3. In combination with an internal combustion engine provided with an intake manifold and a spark controlled rod, an air 85 valve mounted on said rod and communicating with the manifold said air valve being provided with ports, a valve casing provided with ports adapted to register with those of the valve, and means for rotating 90 said valve whereby atmospheric air is permitted to enter the valve.

4. In combination with an internal combustion engine provided with an intake manifold and a spark control rod, a perforated baffle in the manifold, a valve mounted on said rod, said valve comprising a split valve and a split casing, registering ports in said valve and casing, and a tubular connection between the valve and manifold. 95

5. In combination with an internal combustion engine provided with an intake manifold and a spark control rod, a perforated cone baffle in the manifold, a valve mounted on said rod, said valve comprising 105 a valve proper and casing, said valve proper and casing each being composed of similar sections, registering ports in the valve and casing, and a pipe coil connecting the valve casing and manifold. 110

6. The combination of an internal combustion engine provided with an intake manifold, a movable rod in the controlling mechanism of said engine, and a valve fixed upon said rod and adapted to be positively moved by said rod in either direction for controlling a supply of air to said intake manifold. 115

7. In combination with an internal combustion engine provided with an intake 120 manifold, a control rod, and a valve on said rod and communicating with the manifold.

In testimony whereof I hereunto affix my signature this 14th day of November, 1919.

FRANK C. TABLER.
